No. 841,940.

PATENTED JAN. 22, 1907.

H. E. CRANDALL.
HOSE SUPPORTER.
APPLICATION FILED JULY 20, 1906.

UNITED STATES PATENT OFFICE.

HERMAN E. CRANDALL, OF NEW BRITAIN, CONNECTICUT.

HOSE-SUPPORTER.

No. 841,940.

Specification of Letters Patent.

Patented Jan. 22, 1907.

Application filed July 20, 1906. Serial No. 327,032.

To all whom it may concern:

Be it known that I, HERMAN E. CRANDALL, a citizen of the United States, residing at New Britain, in the county of Hartford and State of Connecticut, have invented certain new and useful Improvements in Hose-Supporters, of which the following is a specification.

My invention relates to improvements in hose-supporters; and the main object of my improvement is economy in production, especially in the matter of securing the button-plate to the webbing.

In the accompanying drawings, Figure 1 is a front elevation of the webbing and button member of my hose-supporter as applied to a covered button. Fig. 2 is an enlarged central section of the same with the webbing loosened to better illustrate the same and with the button shown in side elevation. Fig. 3 is a front elevation, on the same scale as Fig. 1, of the webbing before it is attached to the button-plate. Fig. 4 is a front elevation of the button and button-plate without the webbing. Fig. 5 is a sectional view of the button-plate and one end of the webbing passed through one eye of the button-plate to illustrate the first step in securing the said plate to the webbing. Fig. 6 is a front elevation of the button member of my hose-supporter as applied to the button-plate without having the webbing cover the button. Fig. 7 is an enlarged sectional view of the same with the webbing loosened a little to better illustrate the construction, the button being shown in side elevation.

The first two figures of the drawings illustrate my invention with particular reference to the hose-supporter patented to me September 8, 1903, No. 738,713, and in which the webbing to which the button and button-plate are attached is applied so as to cover the button. The present invention is, however, applicable to a button and button-plate without having the webbing cover the button, the latter being illustrated in Figs. 6 and 7. The hose-supporter is of the well-known loop-and-button class, and as the present invention relates solely to the button member the loop member is omitted from the drawings.

In hose-supporters in which the webbing extends through and partly around the button-plate without extending over the button

it has hitherto been necessary to sew or otherwise secure the webbing in order to retain the button-plate and button thereon. In my patented hose-supporter such sewing is not necessary; but in practice it has been found desirable to provide the end of the tape or webbing with a metal tip in order to prevent raveling and to prevent the said end from drawing through the eye or eyes of the button-plate. By my present invention I save the expense of sewing or otherwise fastening the webbing in the form of supporters illustrated in Figs. 6 and 7 and save the expense of the metal tip in the form of supporters illustrated in Figs. 1 and 2.

The button-plate or button-base 8 and connected button 9 are of an ordinary construction. The webbing or tape A is in the main of an ordinary construction and is first cut into the desired length, and then the tip or end 10 is dipped into and coated or imbued with a liquid gum, glue, cement, or other material that will harden in drying and is then left to dry, thereby producing the tipped tape or webbing illustrated in Fig. 3, in which the threads comprising this ordinary soft and flexible webbing are hardened and stuck together or united in the said tip, which is harder and stiffer than the rest of the said webbing. That portion of the tip which is thus hardened by the application of a hardening material is represented by cross-lines. The length of the hardened tip should be about the same or a little in excess of the distance from the lower to the upper eye of the button-plate.

The prepared webbing, with the dried and hardened tip 10, has its untipped or soft end first threaded through the lower eye of the button-plate 8 from the rear and drawn along until its passage through the said eye is arrested by the hardened tip coming in contact with the rear side of the plate, as illustrated in Fig. 5. If the webbing is to cover the button, it is then passed up over the button in front and its soft end passed through the upper eye of the button-plate from the front, then down in the rear of the hardened tip and through the lower eye of the button-plate from the rear, then down around the lower end of the button-plate and up in the rear of all the parts, then through the upper eye from the rear, and upwardly, as shown in Figs. 1 and 2. Only the webbing will be drawn

up tightly to make the several thicknesses lie closely together. The hardened end or tip will prevent that end of the web from raveling and will also form an obstruction against the said end passing through the eye, so that the button-plate and attached button are firmly and permanently secured to the webbing. By the employment of the dipped and hardened tip the tip may be made longer than the ordinary metal tip, so as to substantially cover the rear of the button-base, while at the same time it is much lighter than a metal tip and is less bulky as to thickness.

In the style of button member shown in Figs. 6 and 7 the same webbing is employed and substantially the same button and button-plate, only the head of the button is made a little larger. The webbing is first inserted in the same manner as before and as illustrated in Fig. 5, after which it is drawn down around the end of the button-plate, up on the rear of the said plate, and through the upper eye from the rear and then upwardly, as shown. The tipped end 10 is so stiff and

hard that it will not draw through, and as it 25 will not ravel the button-plate is securely and permanently attached without any sewing or other additional fastening.

I claim as my invention—

1. In a hose-supporter or analogous article, 30 a button member comprising a button-base having eyes therein and a webbing having its end imbued with hardening material to form a tip, said webbing being threaded through the eyes of the button-base with the tip in 35 position to prevent the tipped end of the webbing from being drawn through the eye.

2. In a hose-supporter or analogous article, the combination of a plate having an eye therein, a soft and flexible webbing formed of 40 threads passing through said eye and having one end imbued with hardening material to form a tip which acts as a stop to prevent the webbing from being drawn through the eye.

HERMAN E. CRANDALL.
